The single figure is a front perspective view of an elevator car entrance with signal fixtures in the entrance columns, showing my new design. The rear of the entrance is essentially plain and devoid of ornamentation.

The broken line showing is for illustrative purposes only.

This application is a division of design application, Ser. No. D. 7,969, filed July 25, 1967, and now abandoned.

I claim:

The ornamental design for an elevator car entrance with signal fixtures in the entrance columns, substantially as shown and described.
